UNITED STATES PATENT OFFICE.

CHRISTOPHER S. DEIBEL AND LESLIE E. LAWLOR, OF YOUNGSTOWN, OHIO.

FLAG-HOLDER.

1,308,340.

Specification of Letters Patent.

Patented July 1, 1919.

Application filed November 21, 1917. Serial No. 203,175.

To all whom it may concern:

Be it known that we, CHRISTOPHER S. DEIBEL and LESLIE E. LAWLOR, citizens of the United States, and residents of Youngstown, 5 in the county of Mahoning and State of Ohio, have invented certain new and useful Improvements in Flag-Holders, of which the following is a specification.

This invention relates to flag holders of 10 that type adapted to be operated by wind pressure for rotating a plurality of flags, and relates more particularly to certain detail improvements in the structure disclosed in our copending application filed July 18, 15 1917, Serial No. 181,368.

An object of the present invention is to reduce the noise of operation of the rotatable parts to a minimum; to simplify the construction by reducing the number of parts 20 disclosed in our prior device above referred to; to eliminate all parts of time consuming and expensive production; to produce a holder of relatively light weight and compact form; and to provide a device wherein 25 the wind wheel may gain momentum, and subsequently may be automatically coupled with the turn table or flag support to rotate the same.

The invention embraces the above, and 30 various other important features, of construction hereinafter or particularly set forth in the following detailed description of the present preferred embodiment, the same being illustrated in the accompanying 35 drawing, wherein:

Figure 1 is a front elevation of a flag holder constructed according to the present invention.

Fig. 2 is a side elevation thereof applied 40 to the neck of an automobile radiator, parts being shown in sections.

Fig. 3 is a fragmentary bottom plan view of the turn table and frame.

Fig. 4 is a detail side elevation, enlarged, 45 of the flag supporting clip as applied to one of the flag staffs.

Fig. 5 is an outer edge view of the same.

Fig. 6 is a transverse section through the clip as applied to the flag staffs, taken on the 50 line 6—6 of Fig. 4.

Referring to the drawing, 10 designates a frame which is preferably constructed from a single length of strap metal looped into circular form intermediate its ends and having 55 its return end portion in face engage-

ment and secured together by a rivet 11 or the like, to form a bracket arm extending radially from the frame 10. One free end of the strip is bent substantially circularly to engage about the neck A of a radiator 60 of a motor vehicle or the like, and the opposite end of the strip is curved in a reverse direction adapted to engage about the neck A and meet the extremity of the other end of the strip. A clamping bolt 12 secures 65 the free ends of the strip together in binding relation about the neck A, the free ends of the strip forming clamping jaws 13 and 14.

The frame 10 is adapted to be supported in substantially a horizontal plane in front 70 of the radiator, and is provided with a diametrically extending brace arm 15 in the form of a strip of metal downturned at opposite ends and riveted or otherwise suitably secured to the opposite side portions of 75 the frame 10. The arm 15 is apertured intermediate its ends to provide a bearing, and the arm is provided at one lateral edge opposite the bearing with a depending and downturned tongue 16 having a reduced 80 opening therethrough adapted to form a reduce bearing, the tongue 16 being bent into position to vertically aline the upper and lower bearings. The tongue 16 is formed 85 upon the rear edge of the arm 15, and the other or forward edge of the arm is provided with a depending flange 17, the flange being apertured to form a bearing. The circular body portion of the frame 10 is also provided with an opening or bearing portion in 90 its front side in longitudinal alinement with the bearing in the flange 17.

Mounted upon the frame thus constructed 95 is a turn table, the same comprising a pair of disks 18 and 19 which are preferably of concavo-convex form with the convex faces extending upward, and with their marginal edge portions slightly spaced apart to form a peripheral groove adapted to receive therein an annular friction ring 20 of rubber or 100 the like. The disks 18 and 19 are secured together by rivets 21 and are adapted to bind the friction ring 20 in the annular groove. The turn table is provided, axially, with a depending shaft 22 having a head on 105 its upper end seating against the upper face of the disk 18 and having a collar spaced below the head, as at 23, adapted to engage against the lower disk 19 to hold the shaft 22 from longitudinal movement to the turn 110

table. The shaft 22 projects down through the bearing in the arm 15 and has a reduced extremity seated in the lower bearing of the tongue 16, a pair of lock nuts 24 being threaded upon the lower extremity of the shaft 22 and below the tongue 16 to retain the shaft from upper displacement from the frame. The lower reduced ends of the shaft 22 forms an annular shoulder adapted to seat upon the lower end of the tongue 16 for supporting the shaft 22 from downward movement. The turn table is thus supported in suitably spaced relation above the frame 10 and is adapted to freely turn with the shaft 22.

The turn table thus formed is provided with a number of upwardly extending and preferably outwardly inclined staffs 25 threaded at their lower ends into the disks 18 and 19 and provided with lock nuts 26 for retaining the staffs in position. Each staff 25 is provided intermediate its ends with a collar 27, supported or otherwise suitably formed upon the staff, and is provided 25 upon its upper end with a cap 28 of any tangible configuration having an outstanding flange at the upper end of the staff. Each staff 25 is provided, between the collar 27 and the head 28 with a flag connecting 30 clip which preferably comprises an integral sheet metal blank returned upon itself and cut away at its intermediate portion to provide, at the bend of the blank, eyes or loops 29 encircling the staff 25 to rotatably support the clip thereon. The lower eye 29 engages the shoulder 27 to hold the clip from 35 sliding down upon the staff 25, and the head 28 engages the upper eye 29 to hold the clip from rising on the staff. The free end portions of the blank are brought together against the opposite side of the flag body 30, as shown in Fig. 6, and are secured thereagainst by rivets 31 or the like, and also by indentations 32 which are pressed into the 40 fabric of the flag body 30. The clip blank is provided at opposite ends with tongues 33, one tongue being disposed upon each end, and the tongues being turned over the opposite lateral portion of the blank when the latter is folded, as shown in Figs. 4 and 5. The tongue 33 serves to hold the free edge portions of the blank from bending outwardly from the flag body 30. The clip thus constructed is free to turn upon the staff 25 so as to follow the flag body 30 which may freely wave in any direction about the staff 25 without winding about the staff.

Rotatably mounted in the frame 10 is a 45 forwardly projecting spindle 34 which engages through the bearing in the front side of the frame and also in the bearing in the flange 17. The spindle 34 is held from forward sliding movement through its bearing 50 by a head 35 carried upon the inner end of

the spindle and which is adapted to engage the flange 17. Fixed upon the forward end of the spindle 34 is a friction disk 36 provided with a forwardly projecting up portion to which is fixed a wind wheel 37 of any suitable construction, and which is adapted to be turned by wind pressure thereagainst. The friction disk 36 is spaced forwardly upon the spindle 34 a distance sufficient to admit of the longitudinal shifting of the spindle 34 in each bearing and admit of the movement of the disk 36 toward and from the friction ring 20 of the turn table. The spindle 34 is shiftable to admit of the free rotation of the wind wheel with its friction disk 36 to gain momentum before the wind pressure against the wind wheel 37 is sufficient to slide the spindle 34 backwardly and engage the disk 36 with the friction ring 20 of the turn table. Thus, the wind 55 wheel is permitted to gain sufficient momentum to overcome any friction or resistance on the part of the turn table to turn it. As the friction disk 20 is made of rubber, or other suitable resilient material, the noise produced by the engagement of the turn table with the friction disk is considerably reduced over the structure disclosed in my prior application wherein intermeshing gears were employed. During the turning of the staff 25, the flag clips are held in one direction by the wind pressure against the body portion 30 of the flag, and the flags are retained from winding about the staff 25.

The clips may be readily released from the flag body 30 by merely turning the tongue 33 outwardly from engagement with the opposite edge portion of the blank and spreading the edges apart, the studs 21 being thus freed from the side of the body provided with the apertures for receiving the studs. The flag body 30 may thus be easily removed from the studs and substituted with another flag body. When the flag 30 is engaged over the studs 31, the parts of the clip may be pressed together and held in such position by the tongues 33, the indentations 32 pressing into the fabric of the flag and retaining it firmly from pulling out between the studs 31.

It is of course understood that various changes of construction and design may be made in the above specifically described embodiment of this invention without departing therefrom, such changes being restricted only by the scope of the following claims.

We claim:

1. In a flag holder, the combination of a supporting frame, a turn table rotatably carried by the frame and adapted to support a row of flags, a spindle projecting forwardly from the frame, a friction disk mounted on the spindle, an annular friction ring upon the marginal edge of the turn table and adapted to engage said fric- 125 130

tion disk and a wind wheel connected to the disk for turning the same to rotate the said turn table.

2. In a flag holder, the combination of a bracket adapted for detachable engagement with a support, a turn table mounted for rotation on the bracket and adapted to support a circular row of flags, a longitudinally shiftable spindle journaled in the bracket and projecting forwardly therefrom, a friction disk fixed to the spindle, and a wind wheel connected to the disk for turning the same, said wind wheel being adapted for rotation by wind pressure to turn the disk and being adapted to shift the spindle inwardly to engage the disk against the marginal edge of the turn table by wind pressure to rotate the turn table by the disk.
3. In a flag holder, the combination of a bracket frame adapted for attachment to a motor vehicle, a turn table rotatably mounted upon the frame, a plurality of flag staffs upstanding from the turn table, clips rotatably mounted upon the upper ends of the staffs and having edge portions adapted to bind the flag body therebetween, means for detachably holding the edge portions in clamped engagement against the opposite sides of the flag body, and means for turning the turn table.

4. In a flag holder, the combination of a rotatable support, a staff upstanding from the support, a clip rotatably mounted upon the upper end of the staff and provided with overturned edge portions, and a flag body engaging at its inner edge between said edge portions of the clip, one edge portion of the clip provided with studs adapted to engage through said flag body and into the opposite edge portion of the clip, and tongues mounted on opposite ends of the clip and adapted to bend for binding the edge portions in clamping engagement against the opposite sides of the flag body.

5. In a flag holder, the combination of a bracket frame adapted to be secured to a support, a turn table mounted upon the

bracket frame and a longitudinally shiftable spindle journaled in the bracket frame and extending forwardly therefrom, a friction disk fixed on said spindle, a wind wheel fixed to the spindle adapted to turn the said spindle and said disk, said wind wheel being adapted to rotate the disk by wind pressure, and to subsequently shift said spindle rearwardly by wind pressure and bind said disk against said turn table, and a friction ring mounted in a peripheral edge of the turn table for contact with said disk.

6. In a flag holder, the combination of a bracket frame adapted to be secured to a support, a turn table mounted for rotation on the frame, a longitudinally shiftable spindle journaled in the bracket frame and extending forwardly therefrom, a wind wheel fixed to said spindle, means for rotating said turn table by rotation of said wind wheel, said wind wheel adapted to shift said spindle rearwardly by wind pressure and cause said means to operatively engage the turn table to rotate the latter by rotation of the wind wheel.

7. In a flag holder, the combination of a bracket frame adapted for attachment to a motor vehicle, a turn table rotatably mounted upon the frame, a plurality of flag staffs upstanding from said turn table, clips rotatably mounted upon the upper ends of said staff and having edge portions adapted to bind the flag body therebetween, means for detachably holding said edge portions in clamped engagement against the opposite sides of the flag body, a longitudinally shiftable spindle journaled in said frame and extending forwardly therefrom, a wind wheel fixed to said spindle, means for rotating said turn table by rotation of said wind wheel, said wind wheel adapted to shift said spindle rearwardly by wind pressure and cause said means to operatively engage the turn table to rotate the latter by rotation of the wind wheel.
